UNITED STATES PATENT OFFICE.

GEORGE H. SELLERS, OF WILMINGTON, DELAWARE, ASSIGNOR TO WILLIAM SELLERS AND JOHN SELLERS, JR., OF PHILADELPHIA, PENNSYLVANIA.

SLEEVE-NUT AND THE METHOD OF MAKING SLEEVE-NUTS.

SPECIFICATION forming part of Letters Patent No. 236,723, dated January 18, 1881.

Application filed September 9, 1878.

To all whom it may concern:

Be it known that I, GEORGE H. SELLERS, of the city of Wilmington, New Castle county, and State of Delaware, have invented a new and 5 Improved Wrought-Iron Sleeve-Nut, of which improvement the following is a specification.

My invention relates to that class of wrought-iron couplings which connect tension-bolts, such as are used in bridge and roof and other 10 trusses; and it consists of a right-hand nut, a left-hand nut, and the sleeve proper which unites the two nuts, the length of this intermediate sleeve being proportioned to the amount of adjustment required. Such sleeve-nuts have heretofore been constructed, so far 15 as I know, in two forms—one with the sleeve cylindrical inside and outside, and the nuts hexagonal at the ends, enlarging toward and vanishing in the round sleeve, the other with 20 hexagonal exterior and parallel sides from end to end, and the interior of the sleeve cylindrical. Both these forms have the end sections thickened up to receive the thread. In both 25 of these forms there is a surplus of metal which is necessarily unequally distributed, producing unequal sections longitudinally, so that this surplus gives additional weight without additional strength, and requires a corresponding increase in the other parts of the structure to 30 sustain it. With the cylindrical sleeve the tapered hexagonal ends afford a very insecure hold for the wrench required to adjust the nut, and the hexagonal sleeve with parallel sides from end to end gives a clumsy appearance to 35 the structure with the largest surplus of metal.

It is the object of my invention to furnish a wrought-iron sleeve-nut having the sleeve with a polygonal exterior and a polygonal or cylindrical interior uniting cylindrical nuts of a diameter 40 less than that of the sleeve, the thickness of metal in the longitudinal section being as nearly uniform as is compatible with proper bearing-surfaces for the wrench, thus affording a wrought-iron sleeve-nut with no surplus metal, and with an outline architecturally correct.

In the accompanying drawings, which form part of this specification, Figure 1 is an exterior longitudinal view of my improved sleeve-nut. Fig. 2 is a cross-section upon the line *a*

b, Fig. 1, representing a cylindrical interior to the sleeve. Fig. 3 is a similar section representing a hexagonal interior to the sleeve conforming with the exterior. Fig. 4 is a longitudinal section of the sleeve-nut on the line *c* 55 *d*, Fig. 3.

I make these sleeve-nuts from wrought-iron plates, cut to proper lengths and widths, according to the size required, so that each plate will make a sleeve-nut. These plates are 60 heated and bent so as to form a cylindrical tube. They are then brought to a welding heat and forged upon a mandrel in dies which give to the whole exterior the form desired in the finished sleeve proper—that is, the central 65 section. The diameter of this mandrel should be such that the interior of the sleeve will be larger than the bolts which are to be connected, and the shape of the mandrel that of the desired interior form of the sleeve. When the 70 tube has been thus formed in the forging-dies, the section of metal on any line parallel with the axis will be uniform throughout. The mandrel is then removed and a smaller cylindrical mandrel of the diameter required for the bottom 75 of the thread of the bolt is placed in this tube, both ends of which, at the same heat, are now forged in dies having cylindrical ends of the outline desired for the nuts, and with the center cut out, so as not to touch that part of 80 the tube which constitutes the sleeve. This forging will reduce the hole at both ends of the tube to the proper diameter, slightly increasing the section of the metal in the ends without materially affecting the shape or section 85 of the sleeve, so that the section of metal remains nearly uniform throughout. To correct any slight defect the sleeve should be returned to the dies which first formed it, where a few blows of the hammer will complete the 90 forging operation. The right and left hand screw-threads are then cut in the ends, and the sleeve-nut is complete. All of these operations severally are well understood, and I have given the above description as the best 95 method known to me for making my improved sleeve-nut, and not as intending to claim as new any one of the several forging or shaping operations mentioned independent of the others; but I do not confine myself to this par. 10

ticular mode of forging this sleeve-nut from a single plate, as it may be done by forging two halves of the tube to the proper shape, and then welding them together on the smaller 5 cylindrical mandrel mentioned; or the preliminary tube may be formed of two or more pieces and then welded and shaped, as hereinbefore described.

Having thus described the nature and object of my invention, what I claim as new, and desire to secure by Letters Patent, is—

1. The process, substantially as hereinbefore described, of making a wrought-iron sleeve-nut by forging a tube in polygonal dies

and upon a mandrel of the desired shape, and 15 then forging the ends in cylindrical dies upon a smaller mandrel.

2. A wrought-iron sleeve-nut made by forging a tube in polygonal dies and upon a mandrel of the desired shape, and then forging the 20 ends in cylindrical dies upon a smaller mandrel, substantially as and for the purposes described.

GEO. H. SELLERS.
